United States Patent Office

Des. 232,211

Patented July 30, 1974

232,211

COMBINATION LITTER CONTAINER AND ADVERTISING DISPLAY DEVICE

Walter Kay, 815 S. 18th St., Arlington, Va. 22202, and
Raymond M. Poelvoorde, Birmingham, Mich.; said
Poelvoorde assignor to said Kay

Continuation-in-part of design application Ser. No.
226,383, Feb. 14, 1972, now Patent No. 229,279,
dated Nov. 20, 1973. This application Dec. 8,
1972, Ser. No. 313,350

Term of patent 14 years

Int. Cl. D20—99

U.S. Cl. D7—191

FIG. 1

FIG. 2

FIG. 3

FIG. 4

FIG. 1 is a perspective view of the combined litter container and advertising display device in closed position showing our new design;

FIG. 2 is a perspective view of the container in open position;

FIG. 3 is a side elevational view of the closed container; and

FIG. 4 is a bottom plan view thereof.

This is a continuation-in-part of design application Ser. No. 226,383, filed Feb. 14, 1972, now Design Patent No. 229,279, dated Nov. 20, 1973.

We claim:

The ornamental design for a combined litter container and advertising display device, substantially as shown and described.
